UNITED STATES PATENT OFFICE.

CHARLES JAMES APPLEBY, OF SOUTHWARK, COUNTY OF SURREY, ENGLAND.

SHAFT-BEARING FOR TRAVELING CRANES.

SPECIFICATION forming part of Letters Patent No. 291,861, dated January 15, 1884.

Application filed October 22, 1883. (No model.) Patented in England December 22, 1879, No. 5,226.

To all whom it may concern:

Be it known that I, CHARLES J. APPLEBY, of Southwark, in the county of Surrey and Kingdom of Great Britain, have invented a new and useful Improvement in Shaft-Bearings for Traveling Cranes and Similarly Traveling Devices, which improvement or invention is fully set forth and illustrated in the following specification and accompanying drawings, and for which invention Letters Patent of Great Britain were duly issued to me, numbered 5,226, dated the 22d day of December, 1879, and sealed the 18th day of June, 1880.

The object of the invention is to provide a bearing or number of bearings for a rotary or other shaft, which bearings shall be successively and automatically moved out of the way of a traveling crane or similar device, or some part thereof to which such revolving shaft may be connected, and again restored to support said shaft after the crane or some similar traveling device shall have successively passed beyond such bearings.

To this end the invention consists of the parts hereinafter described, as set forth in the claims.

In the said drawings, Figure 1 is a perspective view of the invention, showing parts of a crane traveling past one bearing after having depressed said bearing out of its way. Another bearing is also shown to be similarly operated as the crane progresses. Fig. 2 is a geometrical side view of one bearing and operative attachments, partly in section.

In said figures, the letter A indicates a rotary shaft, and B a vertical hollow bracket fixed against a wall, C. The arm D turns upon a journal, E, and has at its outer end a bearing, F, which supports the shaft A. A rocker-arm, G, turns upon a lower journal, H, and its outer end, when raised, lifts with it the arm D until the bearing F is in its proper position, when said outer end engages with the catch or shoulder I, so as to firmly support the arm D. The rocker-arm G has also an inner end formed into a shorter counterbalance-arm, I', jointed to the vertical rod or bar K, which rod is suitably guided by the bracket B, and the upper end of which is fitted with a slotted head or slide, L. The plate or bar M is attached to the traveling crane O, or

other machinery which has to pass along the shaft A, and it carries at its lower edge a double inclined or curved bar or cam, N, which fits into and passes through the slotted head 55 L of the rod K, Fig. 1, as the crane travels along the shaft A, which is shown square in section (except at its journals) for driving the traveling pulley. It can now be readily perceived that the respective inclines or curvatures given to the bar N at its ends are such that the advancing end of said bar, (in whichever direction the bar may travel,) when it enters the slotted head L of the bar K, must raise said head and pull upon the bar K, which 60 in turn raises the counterbalance-arm I', and depresses the arm G, throwing it out of engagement with the arm D, which immediately descends, following the arm G by gravity, and carrying with it the bearing F, away from and 70 below the shaft A, as shown in dotted lines in Fig. 2. As long as the central portion of the bar N, which is straight, remains within the slotted head L, the bearing B will remain depressed; but when the rear or following end 75 of the cam-bar N is passed through the slotted head L, it is equally evident that its shape is such that it will depress said head and the rod K, and thus, through the intervention of the arms I and G, elevate the arm D and bearing F, to again support the shaft A, the arm G again engaging with the catch or shoulder I on the arm D. Of course this raising of the arm D only takes place after the part or pulley to which it is an obstruction has passed 85 beyond it, and it remains up in place until again displaced, as just described.

The shaft A may be round in cross-section, instead of square, if preferred, and fitted with a feather or feathers for pulleys driven by it 90 and traveling upon it. It is obvious, also, that the rod K may be made to operate the rocker-arm G from below instead of from above, as shown in the drawings, a push being imparted to said rod in such case, instead of a pull, in 95 order to effect the same movement of the bearing D.

I do not confine myself to the precise forms of construction herein shown and described, as the same may be varied in mechanical detail and arrangement without departing from 100 the invention itself.

Having thus fully described my said improvement, as of my invention I claim—

1. In combination with a pivoted bearing for a rotary or other shaft, a counterbalanced rocker-arm supporting said bearing, and a rod or bar connected to said rocker-arm for actuating the same, substantially as and for the purposes set forth.

2. The combination of a pivoted bearing for a rotary or other shaft, a rocker-arm support-

ing said bearing, a rod or bar connected to said rocker-arm, and a moving or traveling cam operating said rod, whereby said bearing is automatically depressed and elevated, substantially as and for the purposes set forth.

CHARLES JAMES APPLEBY.
